Application July 13, 1940, Serial No. 345,260

12 Claims. (Cl. 178—2)

This invention pertains to telegraph systems and particularly to such systems designed for the propagation in broadcasting manner from a central station to a plurality of substations of messages varying principally in content rather than in form.

An object of the invention is to provide a transmitter which includes settable apparatus for predetermining a message form, supplemented by settable apparatus for inserting into a formal message certain character signals as will convey specific information.

In combination with the indicated principal transmitter for formal messages, a subordinate transmitter for messages of unlimited content and free of restrictions of form is provided.

A further object of the present invention accordingly is to provide locking devices and interfering devices such that a principal transmitter may seize the transmission system in preference to a subordinate transmitter and may continue uninterruptedly the transmission of a formal message when begun.

Another object of invention is the provision of a system offering great facility for switching portions of a central office apparatus from a general transmission system and for including said apparatus in a local circuit for test and adjustment purposes.

Other features of invention are to provide mechanism for establishing code signals for indicating time, and to provide mechanism for producing a variable charging rate for a storage battery in accordance with the load placed upon the battery.

The noted objects are attained by a system of apparatus and circuits embodying a manual keyboard for setting up an omnigraphic formal message, a start-stop code-signal transmitter, stepping switches for establishing time signal conditions and further stepping switches for connecting the keyboard to the code-signal transmitter for selecting keyboard members, fixed signal members and time signal members, and for selecting predeterminedly thereamong. A start-stop telegraph set of any desired type may be used as a subordinate transmitter and home recorder at the central office. At a substation, a start-stop recorder without transmitter, and with motor, battery and battery charger are provided.

A more complete understanding of the invention may be obtained from the following description, taken in conjunction with the accompanying drawings, in which

Fig. 1 illustrates a transmitter for formal messages;

Fig. 2 shows details of key construction;

Fig. 3 shows a general circuit diagram of the central office system which should be placed directly below Fig. 1 with the correspondingly numbered conductors matched to show the complete system;

Fig. 4 shows a circuit diagram of a substation; and

Fig. 5 shows a sample section of the tape printed, through the operation of the system.

In brief preview, the principal parts of the invention are as illustrated and identified by reference numerals in Figs. 1, 2, and 3.

Fig. 1 illustrates a set of apparatus constituting a transmitter for formal messages, and within rectangle 31, Fig. 3, are symbolized a recording tape-printing receiver 32 and a code signal transmitter 33 which may be respectively, according to U. S. Patent 1,745,633 to S. Morton et al. and U. S. Patent 1,595,472 to Krum, which together with a motor 34 and a lamp 35 form a complete recording and transmitting telegraph set. A duplicate set of apparatus for formal messages is provided, connected to conductors 36 while rectangle 37 encloses a duplicate of apparatus shown in rectangle 31. Local repeating relays 40 and 41 are provided for repeating transmitted telegraph signals into local circuits and a plurality of duplicate line relays 42 are provided for repeating transmitted telegraph signals into line circuits.

35 A first transmission system of apparatus in the central office includes the transmitter of Fig. 1 for transmitting formal messages, the telegraph set of rectangle 31, Fig. 3, for home recording and for transmission of messages of unlimited content, a multi-pole switch 43 and the local repeating relay 40, all in association with control relays 44, 45, 46, a reversing relay 47 and transmitting line relays 42. A second or 40 duplicate transmission system of apparatus in the central office includes a duplicate of transmitter, Fig. 1, the telegraph set of rectangle 37, a multi-pole switch 48, and a reversing relay 49, all in association with repeating local relay 41 and repeating line relays 42.

45 Local testing systems in the central office comprise the local repeating relay 40, reversing relay 47 and switch 43 for test of apparatus of Fig. 1 and rectangle 31 and alternatively the local repeating relay 41, reversing relay 49 and switch 48 for test of the duplicated appara-

tus of Fig. 1 connected to conductors 36, and of rectangle 37.

Four transmission lines are indicated in Fig. 3, each line having five substations 51, of which one substation is illustrated in Fig. 4 by detailed circuits which are connected to apparatus of Fig. 3 through line conductors 52 and 53.

In greater detail, a pilot switch 60, Fig. 1, of stepping design has bank contacts which are connected through conductors in cable 61 and contacts of manual keys 62 to a signaling circuit conductor 63, or through conductors 64 and contacts of other manual keys 65 to the conductor 63, or through conductors in cable 66, bank contacts and brushes of time-signal switches 67, conductor 68 and cam controlled contacts 69 to the conductor 63, while still further bank contacts of pilot switch 60 are connected directly and permanently to conductor 68 and through contacts 69 to the conductor 63. A start-stop distributor 72 which may be according to Patent 1,595,472 noted above, has its stop-signal contact connected to conductor 63 and has its code-signal contacts between brushes of pilot switch 60 and a signal circuit conductor 73. The distributor 72 is driven by a start-stop main shaft 74, there being a power clutch 75 to be operated to start by mechanical action of armature of magnet 76 and arranged to be retained in operated condition thereafter by a latch 77 controlled by a cam 78 on cam shaft 80 to make three pilot switch revolutions following each start in response to momentary operation of the starting magnet 76. Further cams on cam shaft 80 control other contacts of which the functions will be described in connection with description of circuits in which they severally are included. Main shaft 74 carries a cam 79 which once in each rotation engages a pawl 81 and operates the pawl to drive a ratchet 82 through 3 degrees of angle, thus driving the shaft 80.

Pilot switch 60 comprises a rotary stepping shaft 83 carrying six double-end brushes 84 and a ratchet 85 driven by a pawl 86 on armature 87 of magnet 88. Three similar switches 91, 92, 93, constitute a generator of time indicating code signals. In all such switches, bank levels are numbered 1 to 6, each bank having twenty-five contacts and a feed brush 94 for each double-end brush is connected through a first terminal, as exemplified in switch 91.

Five conductors 95 connect code contacts of transmitter 72 to the first contacts of levels 1 to 5 in pilot switch 60. In keybank 62, operation of any manual key will close the contacts illustrated adjacent thereto. Operation of any one of the manual keys 65 will connect the signaling circuit conductor 63 through selected conductors 64 to the fifth, sixth, seventh, eighth, ninth, tenth and eleventh contacts in levels 1 to 5 selectively of pilot switch 60 for the purpose of setting up variant combinations of an electrical potential on the noted bank contacts. In like manner, operation of any thousands keys 96 will connect the signaling circuit conductor 63 through selected conductors 61 to the fourteenth contacts in levels 1 to 5 selectively, operation of any hundreds key 97 will connect conductor 63 to the fifteenth contacts in levels 1 to 5 selectively, operation of any tens key 98 will connect conductor 63 to the sixteenth contacts in levels 1 to 5 selectively, and operation of any units key 99 will connect conductor 63 to the seventeenth contacts in levels 1 to 5 selectively. Permanently connected to conductor 63 are certain of the third, fourth, tenth, twelfth, thirteenth and eighteenth

bank contacts in pilot switch 60 as indicated in Fig. 1 while other indicated contacts in the first, second, twenty-second and twenty-fifth switch positions are permanently connected to conductor 68 which is electrically connected to conductor 63 when cam controlled contact 69 is in closed condition.

In detail, operation of prefix key 101 connects conductor 63 through conductor 108 to the tenth contacts in levels 1, 2 to form a code signal for A, and connects conductor 63 through conductor 109 to the eighth contacts in levels 1, 4, 5 to form a code signal for B, and also connects conductor 63 through conductor 109 to the fourth contact in level 3 to change to "letters shift" code signal (1, 2, 3, 4, 5) the code signal that is permanently connected to the fourth contacts in the other four levels for "figures shift" (1, 2, 4, 5).

Operation of prefix key 102 connects conductor 63 through conductor 110 to the sixth contacts in levels 3, 4, to form a code signal for N and key 102 also connects conductor 63 to conductor 109 to form code signals for B and "letters shift" as described.

Operation of prefix key 103 connects conductor 63 through conductors 111, 112, 115 to the fifth, seventh and ninth contacts in levels 1, 2, 5 to form a code signal for 2.

Operation of prefix key 104 connects conductor 63 through conductors 111 to the fifth, seventh and ninth contacts in level 1 to form a code signal for 3. Key 105 operates as described for key 104 but adds a connection from conductor 63 through conductor 117 to the eleventh contact of level 1 to form a code signal for 3.

Operation of prefix key 106 connects conductor 63 through conductors 112, 114 to the fifth, seventh and ninth contacts in levels 2, 4 to form a code signal for 4. Key 107 operates as described for key 106 but adds a connection from conductor 63 through conductor 118 to the eleventh contact in levels 2, 4 to form a code signal for 4.

Thousands keys 96 each connect conductor 63 to the fourteenth contacts of levels 1 to 5 selectively to form that code signal indicated on the symbol of the key. Similarly, hundreds keys 97 connect conductor 63 to the fifteenth contacts selectively, tens keys 98 connect conductor 63 to the sixteenth contacts selectively, and units keys 99 connect conductor 63 to the seventeenth contacts selectively.

By permanent connections with conductor 63 there are set up in pilot switch 60 a code signal for double dash on the third and eighteenth contacts in levels 1, 3, 4, a code signal for figures shift on the fourth and twelfth contacts in levels 1, 2, 4, 5, a code signal for hyphen on thirteenth contacts of levels 1, 2, and a code signal for space on the twentieth contact in level 3. When cam controlled contact 69 is in closed condition there are set up further in pilot switch 60 through conductor 68 a marking condition on the first contact in level 3 to establish a space code signal on the first contacts in level 3, a code signal for figure shift on the second contacts in levels 1, 2, 4, 5, a code signal for colon on the twenty-second contacts in levels 2, 3, 4, and a code signal for a time designating symbol AM on the twenty-fifth contacts in levels 3, 4.

The twenty-first, twenty-third and twenty-fourth contacts in levels 1 to 5 of pilot switch 60 are connected to contacts of time code switches 91, 92, 93, respectively, the brushes of those switches being connected to conductor 68. Connections thus are completed when cam controlled

contact 69 is in closed condition by which there are set on the twenty-first contacts code signals representing the digital value of the instant hour under control of switch 91, on the twenty-third contacts code signals representing digital value of the tens of minutes under control of switch 92 and on the twenty-fourth contacts code signals representing digital value of units of minutes under control of switch 93. On pilot switch twenty-fifth contacts the code signal is AM on levels 3, 4 when the conductor 120 which extends to the twenty-fifth contact of level 5 is held disconnected from conductor 68 by level 6 of switch 91 and the code signal is PM on levels 3, 4, 5 when conductor 120 is connected to conductor 68 by level 6 of switch 93 and when cam controlled contact 69 is in closed condition.

Starting circuit for clutch trip magnet 76 extends from ground 121 through lower contacts of manual locking preparatory switch 122, contacts of manual nonlocking starting switch 123 and clutch trip magnet 76 to battery.

Stepping circuits for controlling movement of brushes of the pilot switch 60 are (a) from ground through stepping magnet 88, brush 84, contact 1 in level 6, cam controlled contacts 124, parallel closed contacts 128 and contacts 125 of magnet 88, and local contacts 126 in transmitter 72 to battery, (b) from ground through magnet 88, brush 84, and contact from 2 to 20 inclusive in level 6, and contact 126 to battery, (c) from ground through magnet 88, brush 84, any contact from 21 to 25 inclusive in level 6, conductor 121, closed cam-controlled contacts 128 and contacts 126 to battery, and (c2) from ground through magnet 88, brush 84, any contact from 21 to 25 inclusive in level 6, conductor 121, contacts 125 (contacts 124 being now open) conductor 129 and contacts 126 to battery.

Clock circuits for controlling movement of brushes of time-code switches 91, 92, 93 are (for minutes) through battery, Fig. 3, clock contact 131, conductor 130 and winding of stepping magnet 132 of minutes switch 93 to ground; (for tens of minutes), through battery, clock contact 131, conductor 130, brush and tenth or twentieth contact in level 6 of switch 93, and stepping magnet 133 of switch 92 to ground; and (for hours) through battery, clock contact 131, conductor 130, brush and tenth or twentieth contact in level 6 of switch 93, brush and sixth, twelfth, eighteenth or twenty-four contact in level 6 of switch 92 and stepping magnet 134 of switch 91 to ground. Automatic driving circuits for switches 91, 92 and 93 are through battery, brush and twenty-fifth contact in level 5 of switch 91, contacts 136 and magnet 134 of switch 91 to ground; through battery, brush and twenty-fifth contact of level 5 of switch 92, contacts 137 and magnet 133 to ground; and through battery, brush and any contact from the twenty-first to the twenty-fifth inclusive, in level 5 of switch 93, contacts 138, 139 and magnet 132 to ground. A further time-switch control circuit extends through battery, cam-controlled contact 140, contacts 141, 139 when operated by magnet 132, and winding of magnet 132 to ground.

Keys 62 and 65 are locking manual keys and may be as shown in Fig. 2 where key member 142 operates contacts 143 and is locked in operated position by engagement of locking lug 145 with locking bail 144 common to all keys 62 and 65. Just before shaft 80 completes its cycle a cam 146 engages a follower 147 for operating ball 144 momentarily to unlock all keys.

For operation of the described apparatus, an operator closes the locking manual preparatory key 122, Fig. 1, which completes a local control circuit through ground 121, Fig. 1 upper contacts of key 122, conductor 150 (Figs. 1 and 3), switch 43, conductor 151, reversing relay 47 and battery, thus energizing and operating the relay 47. Prior to operation of relay 47, current had been flowing in a home recorder circuit from battery 152 through armature 153, resistor 154, conductor 155, switch 48, conductor 156, conductor 157, contacts of relay 158, conductor 159, home recorder magnet 160, motor control relay 161, switch 48, conductor 162, switch 43, conductor 163, conductor 164, contacts of relay 45, conductor 165, home recorder magnet 32, motor control relay 44, switch 43, conductor 166, resistor 167 and armature 168 to ground 169. During the ensuing period in which relay 47 retains its operated condition, the described current in the home recorder circuit is reversed in direction, flowing from battery 152 through armature 168, thence through the loop circuit traced above and through armature 153 to ground 170. Reversal of current through polar relays 44 and 161 operates those relays to close their contacts. Relay 44 closes a circuit through ground 121, Fig. 1, lower contacts of switch 122, conductor 171, Fig. 3, contacts of relay 44, windings of relays 45, 48 and grounded battery. While motor control relay 161 is operated to close its contacts, the circuit of those contacts is not closed because of open condition of the preparatory switch corresponding to switch 122 in the duplicate transmitter. Operated condition of relay 45 removes a shunt path including conductor 164 and contacts of relay 45 from contacts of repeating relay 40 and the described loop circuit from battery 152 to ground 170 now includes conductors 172, 173, resistor 174 and contacts of relay 40 which accordingly control operation of the recorder magnet 32. Operated condition of relay 46 connects ground to conductor 175 which closes four circuits for signal lamp 35 and motor 34 of the set 31, Fig. 3, also signal lamp 176 and motor 177 of the transmitter of Fig. 1. Substation motors also have been started by operation of relay 47, as will be described in a description of the substation, Fig. 4.

The transmitter of Fig. 1 now is in condition for operation and the operator accordingly operates into locked condition one key only in each of the key sets 65, 96, 97, 98 and 99, then operates momentarily the starting switch 123, energizing the clutch trip magnet over a described circuit, thus permitting clutch 75 to engage its members to start the rotary transmitter 72. Presume that keys 105 and keys 5 in the sets 65, 96, 97, 98 and 99 have been operated. Transmission and mechanical operations will be as follows:

In its first revolution, transmitter 72 transmits "space" code signal through conductor 68 and contacts 89 from the first contacts in pilot switch 60. Meanwhile, cam 79 operates pawl 81 and shaft 82 one step, whereby cam 78 rotates into its interfering condition to restrain the latch 77 from disconnecting the clutch 75, cam 180 closes contacts 124, cam 181 closes contacts 140, 182, and cam 183 closes two pairs of contacts 184. Cam 185 as yet is ineffective. Contacts 124 prepare a circuit for stepping the pilot switch 60. Contacts 140 prepare a circuit for control of time switches 91, 92, 93. Contacts 182 form a shunt around contacts of subordinate transmitter 33, thereby rendering the subordi-

nate transmitter ineffective. Upper contact of pair 182 is connected over conductor 73 to right-hand terminal of transmitter 33, while lower contact of pair 182 is connected over conductors 186, 187 to left-hand terminal of transmitter 33, thus shunting the subordinate transmitter 33 when the chief transmitter of Fig. 1 is operating and is holding contacts 182 closed. Contacts 184 are connected in parallel with contacts of preparatory switch 122 and render all apparatus continuously operative independently of said key while the chief transmitter is operating. The pilot switch 60 makes three revolutions in response to one operation of clutch magnet 76. Contacts 69 and 128 open at a mean moment in the first revolution of switch 60 and close at a mean moment in the third revolution of switch 60, thereby rendering transmission variant for the several revolutions. The first change in condition of contacts 69, 128 occurs before brushes of switch 60 have engaged the twenty-first contacts in the first revolution and the second change occurs before the brushes have engaged the twenty-first contacts in the third revolution.

Transmitter 72 has six pairs of contacts, each pair controlled by an individual cam on shaft 74. Contact 126 closes and opens while the contact connected to conductor 68 is closed. Contacts connected to conductors 68 and 95 operate in timed relation to transmit Baudot code start-stop signals. Each of the contacts in transmitter 72 connected to conductors 68 closes in every revolution of shaft 74, thus connecting the signal circuit conductor 73 through to conductors 95 serially in order for transmission of each code signal. The transmission conditions of marking or spacing for each impulse of the code signal are determined by the connective condition between brushes of switch 60 and signal circuit conductor 68 and these are predetermined by permanent wiring, by operated contacts in keys 62 and 65 and by brushes in switches 91, 92, 93.

Just before the termination of the first revolution of shaft 74, after starting by magnet 76 as described, contacts 128 open the described "stepping circuit (a)," previously closed at any instant during the revolution. Pilot switch brushes are advanced from the first contacts to the second contacts during the "stop" interval of transmission. Clutch latch 77 is in restrained condition by cam 78, clutch 75 remains engaged and rotation of shaft 74 continues.

In its second revolution, transmitter 72 transmits figures shift code through conductor 68 and contacts 93, and contact 128 closes "stepping circuit (b)" to advance the pilot switch brushes from the second contacts to the third contacts.

In its third, fourth, twelfth, thirteenth, eighteenth and twentieth revolutions, transmitter 72, transmits, respectively, code signals for double dash, figures shift (second occurrence), figures shift (third occurrence), hyphen, double dash (second occurrence) and space, invariably, by permanent wiring of signaling conductor 68 directly to pilot switch contacts. In fifth to eleventh revolutions of transmitter 72, the transmission is determined by setting of a key in key set 65, and in fourteenth to seventeenth revolutions by setting of one key in each of key sets 96, 97, 98, 99.

In each revolution of main shaft 74, the cam shaft 80 has been advanced one step by action of cam 79, pawl 81 and ratchet 82. When pilot brushes reach contacts 21, cam 185 has operated its contacts 69 and 128 into open condition, and

there is no connection for transmission from the twenty-first to twenty-fifth contacts. From the second contacts to the twentieth contacts in the pilot switches, the brushes have been advanced by "stepping circuit (b)." With brushes in engagement with the twenty-first to twenty-fifth contacts, the contact 126 closes "stepping circuit (c2)" and magnet 88 operates in vibrating manner by reason of its contacts 125. Brushes of the pilot switch pass quickly from the twentieth contacts to the first contacts when contacts 128 are open in first and second cycles of operation of pilot switch 60. Transmission in first pilot cycle has been =3333-5555=.

For second cycle of pilot switch 60, transmission from transmitter 72 is blank code signal with brushes on the first and second contacts because conductor 68 is disconnected at cam-controlled contacts 69, the cycle thereafter being completed as in first cycle from the third to the twenty-fifth contacts inclusive, with repetition of transmission noted above.

For third cycle of pilot switch 60, operation is as described for second cycle from the first contacts to the twentieth contacts inclusive, during which time cam 185 has closed contacts 69, 128 and cam 180 has opened contact 124. Transmission from the third to the twentieth contacts inclusive, has been as noted above in first pilot cycle and conductor 68 being now connected to conductor 63 at contacts 69, transmission continues through the twenty-first pilot contacts and time switch 91 to conductor 68, for a code signal representative of the hour, the hours 10, 11, 12 being logotypes transmitted by a single code signal, then through the twenty-second pilot contacts permanently connected to conductor 68 for a code signal for colon, then through the twenty-third pilot contacts and time switch 92 to conductor 68 for a code signal representative of the tens digit of minutes, then through the twenty-fourth pilot contacts and time switch 93 to conductor 68 for a code signal representative of the units digit of minutes, then through the twenty-fifth pilot contacts of levels 3, 4 directly to conductor 68 for a code signal for logotype AM or the twenty-fifth through contacts of levels 3, 4, directly to conductor 68, and jointly through the twenty-fifth contact of level 5 and contacts of level 6, switch 94, to conductor 68 for a code signal for logotype PM, thus effecting; for example, transmission of code signals for 12:32 PM.

Thus, a master control shaft 80 and cams have controlled the rotary pilot switch 60 to select among settable keys 62 and 65, and time register 67 variably in successive revolutions.

Brushes of pilot switch 60 now are advanced by circuit (c) into normal position, engaging the first contacts, the No. 1 contact in level 6 being connected to cam-controlled contacts 124 now open so that a circuit cannot be closed for energization of stepping magnet 88. Shaft 74 has made 75 revolutions, ratchet wheel 82 of 120 teeth has made 75 steps. Shaft 74 makes 35 more revolutions, transmitting space code signal 35 times through pilot brushes on the first contacts and advancing shaft 80 into normal position where cam 78 releases latch 77, which opens clutch 75 at end of next revolution and stops shaft 74.

The total described transmission comprises code signals representing a message, =3333-5555= =3333-5555= =3333-5555= 12:32 PM of which all digits other than time are controlled by keys 62, 65 now restored by cam 146. Should starting switch 123 be operated without

setting any key 62, 65, then a message will be transmitted to print only the permanent or non-settable codes followed by the time codes, thus, = = = = = 12:32 PM.

A local signaling circuit extends through battery 200, Fig. 3, switch 43, conductors 201, 187, subordinate transmitter 33, conductor 73, Fig. 1, chief transmitter 72, conductor 63, Fig. 3, operating winding of local repeating relay 40, conductor 202, switch 43, conductor 203, switch 48, conductors 204, 205, subordinate transmitter 206, conductor 73', duplicated chief transmitter (as 72 not shown), conductor 63', local repeating relays 41, conductor 210, switch 48, conductor 211, and through operating windings of all line repeating relays 42 to ground. In response to control by a transmitter, all repeating relays 40, 41, 42 operate their armature contacts. Normally all transmitters and recorders are inoperative because no motor is running. Contacts of local repeating relays are shunted by contacts of relays 45 and 158.

Central office testing conditions are set up by reversal of switch 43 for test of set 31, Fig. 3, and transmitter, shown in Fig. 1, or by reversal of switch 48 for test of set 31 and duplicate chief transmitter (not shown).

By reversal of contactual relations in switch 43, the local control circuit reformed through battery 152, armature 153, resistor 154, conductor 155, switch 48, conductors 156, 157, contacts of relay 158, conductor 159, recorder magnet 160, relay 161, switch 48, conductor 162, reversed switch 43, conductor 166, resistor 167 and armature 168 to ground 169. The local signaling circuit is reformed through battery 200, reversed switch 43, to conductor 203 and thence as described above, eliminating set 31 and the chief transmitter of Fig. 1 from the local signaling circuit. The described control circuit including conductor 150 is changed in reversed switch 43 from reversing relay 47 to reversing test relay 49. Operating winding of local repeating relay 41 is switched into a local test transmission circuit through battery 215, reversed switch 43, conductors 201, 187, transmitter 33, conductor 73, transmitter 72, conductor 63, operating winding of relay 40, conductor 202, and reversed switch 43 to ground. A home recorder test circuit is formed through battery 216, armature 217, conductor 218, reversed switch 43, relay 44, recorder magnet 32, conductor 165, contacts of relay 45, conductors 164, 163, reversed switch 43, and armature 219 to ground. A lamp 220 signals that the set is on test conditions when motors are started.

Operations and functions of the described test circuits are obvious in light of description above of operation of working signaling circuits.

A plurality of line circuits, as 52, 53, are served by battery 152 and armatures 153, 168 as a source of current supply, and code signaling is effected in each circuit by contacts of line repeating relay 42. When reversing relay 47 is operated to start the central station motors as has been described, current is reversed in all lines 52, 53 to start substation motors, as will be described. Each line circuit serves a plurality of substation equipments 51, one of which is illustrated in detail in Fig. 4.

Line circuit of the substation is from line conductor 52 through motor control relay 230 and recorder magnet 231 to line conductor 53. A test switch 232 when in normal position closes a circuit from relay 230 to motor relay 233, the contact of which, when operated, closes three circuits, for a motor 234, for a signal lamp 235, and for winding of a high-charge relay 236. A manual lock-75

ing switch 237, when operated, shunts the contacts of relay 236. Alternating power current from supply mains 240 energizes a signal lamp 241 and through a transformer 242 provides current for an alarm bell 243 controlled by contacts of low-voltage detector relay 244, connected to storage battery 245, through a ballast resistor 246. Means for charging the battery 245 comprises an auto-transformer 247 having a primary connected to power source 240 and having a secondary connected through space-discharge rectifier 248, a ballast resistor 249, a trickle-charge ammeter 250, a choke coil 251, and the storage battery 245.

For operation, manual switch 122, Fig. 1, and subsequently cam contacts 184 are closed to energize and operate reversing relay 47 which reverses direction of current flow in line conductors 52, 53. Reversal of current in the line circuit, Fig. 4, causes relay 230 to reverse its contactual condition, energizing relay 233 which starts motor 234 and energizes relay 236. Code signals in the line circuit are of neutral or make and break nature and effect recording. A mechanical bias in relay 230 holds the contacts closed during break intervals in the signaling line current. Contacts of operated relay 236 shunt the ammeter 250 and choke coil 251, increasing the battery charging rate to a rate approximating the current consumption of motor 234. Battery 245 may be discharged by open condition of switch 252 and may be recharged at high rate when motor 234 is not running by closed condition of manual switch 237.

To remove the substation set from line control for purpose of test, manual switch 232 is reversed, placing motor relay 233 under control of manual key 253, connecting a signal lamp 256 to indicate that the substation telegraph set is not controlled by the line current, and reversing connections of alarm device 255. When switch 232 is normal, as shown, during receipt of a message, the device 253 will be operated by current through contacts of relay 233. When switch 232 is reversed for purpose of test, device 255 will be operated by current through contacts of relay 230 while no message is being received.

The invention, having been described in connection with an illustration of a specific embodiment thereof, will be definitely pointed out in the appended claims without limitation to the specific illustration utilized herein.

What is claimed is:

1. In a telegraph system, two home recorders, two signal-repeating relays having contacts associated with said two recorders, shunts for the recording contacts of said signal-repeating relays respectively, motors for said home recorders respectively, and common means for starting one of said motors and for removing one of said shunts to qualify one of said recorders for operation in response to one of said signal-repeating relays.

2. In a telegraph system, two home recorders, two signal-repeating relays having contacts associated with said two recorders, shunts for the contacts of said signal-repeating relays respectively, motors for said home recorders respectively, shunt-controlling relays for said shunts, motor-starting relays for said motors, a transmitter connected to supply signals to said signal-repeating line relays, and a circuit through one of said shunt-controlling relays and through one of said motor-starting relays and controlled by said transmitter for starting one of said motors and for opening one of said shunts to qualify one

of said recorders for operation in response to one of said signal-repeating relays.

3. In a telegraph system, motor-driven telegraph recorders, driving motors for said recorders, motor-control means including polar line relays for said motors, a manual key and line-current reversing relay for controlling said polar line relays, a telegraph transmitter for controlling said recorders when driven by said motors, and cam-controlled contacts in said transmitter for controlling said reversing relay for retaining said motors operative independently of said manual key while said transmitter is operating.

4. In a signal transmission system, duplicate transmitting apparatus for alternative service with a common communication channel comprising two supervisory cam shafts, two sets of pilot switches operatively and respectively associated with said cam shafts, means associated with each of said transmitting apparatuses for initiating one of said cam shafts and its associated pilot switch into operation, and interrupting means for preventing the effectiveness of either of said initiating means during the period of operation of the other of said associated cam shafts.

5. In a signal transmission system, a broadcasting circuit, a local test circuit, a pair of keyboard transmitting and recording units, apparatus for optionally associating either one of said units with said broadcast circuit exclusively of the other of said units, a pair of repeating relays each associated with one of said units for producing signals over said local test circuit, and means under the control of each of said units for shunting the effectiveness of the repeating relay associated with the other of said units for thereby mutually excluding the other of said units when one has been seized and operated.

6. In a signal transmission system, two series of signal generating elements comprising in each series an identification signal keyboard transmitter, a time signal transmitter and a printer-transmitter unit, a cyclically operative timing shaft including means for allocating a predetermined interval of transmission for associating with a line cyclically each said identification signal keyboard transmitter and said time signal transmitter, and means subordinated to said timing shaft for permitting said units to be associated with said line when said identification signal and time signal transmitters have completed their cyclic operation.

7. In a telegraph system, a principal timing shaft for regulating cyclic message transmission, a secondary timing shaft having a number of revolutions corresponding to a number of message repeating operations in relation to each cycle of rotation of said principal timing shaft, keyboard means for initiating into rotation said principal and secondary timing shafts, transmitter apparatus cyclically associated with a transmission channel under the control of said secondary timing shaft, and means operative by said principal timing shaft to modify said transmitter association with said secondary timing shaft once for a predetermined plurality of said associations.

8. In an alarm system, a keyboard coding apparatus comprising a set of decimal integer key elements for each of a series of decimal repre-

sentations, a plurality of sets of time integer switches each representative of a time indication decimal, and a cyclically operative pilot switch having a plurality of code component levels including means for connection at certain portions of a cycle with said time digital elements and at other portions of a cycle with said integer key elements.

9. In an alarm transmitting system, duplicate recording and transmitting unit apparatuses, a pair of signal repeating relays associated one with each of said recorders having transmitting contact armatures, means for normally shunting electrically the transmitting contacts of said relays, motors for actuating said recorders respectively, a starting key associated with each one of said recorders, and a reversing relay common to both of said recorders mutually operative to start the motor associated with its particular recorder and remove the shunt from its associated repeating relay for thereby preparing its said associated apparatus for transmission.

10. In a system for broadcasting signals over a loop circuit, a pair of alternatively operable home recorder-transmitter units, each equipped with a printing mechanism for making a home record of matter transmitted over said loop and a keyboard mechanism for generating miscellaneous matter transmission signals, a time signal transmitting apparatus, a keyboard identification code transmitting apparatus, and a pilot switch comprising a rotary member having a plurality of contact levels each associated with a signal component of a permutation code and a number of contact positions in the operative cycle of said pilot switch corresponding to a number of signals predeterminedly associated with said keyboard coding apparatus, said time signal generating apparatus, and said home recorder-transmitter apparatus.

11. In a telegraph broadcast system, a transmitting station apparatus comprising duplicate keyboard transmitter equipments each having a home recording printer, a control circuit including a pair of repeating relays respectively associated with said transmitters, a start key associated with each of said transmitters and with a common circuit, and means associated with each one of said start keys for disabling the other of said start keys from control during the interim of its own operation.

12. In a telegraph transmission system comprising a pair of alternative transmitters, a motor associated with each one of said transmitters, an energizing circuit for each of said motors, and means for selecting for operation one or the other of said alternative transmitters under the control of its motor energizing circuit comprising a pair of polar relays and a reversing switch for normally maintaining the current flow through said relays in one direction and responsive to an individual key associated with each one of said transmitters for reversing the direction of current flow through said relays, and a pair of manual keys, one for each transmitter for supervising the effectiveness of its said transmitter by completing its motor circuit.
